UNITED STATES PATENT OFFICE.

EDWARD CRAIG, OF ST. JOSEPH, MICHIGAN.

BOX-BLANK-GUIDING DEVICE.

1,323,966.

Specification of Letters Patent.

Patented Dec. 2, 1919.

Application filed January 21, 1918. Serial No. 212,873.

To all whom it may concern:

Be it known that I, EDWARD CRAIG, a citizen of the United States of America, and resident of St. Joseph, county of Berrien, 5 and State of Michigan, have invented a certain new and useful Improvement in Box-Blank-Guiding Devices, of which the following is a specification.

This invention relates to stapling machines of that kind in which a guiding and supporting device having guiding means at one end and staple-clenching means at the other end is employed for guiding a folded carton blank into position to have the upper 15 and lower flaps or over-lapped portions thereof fastened together by a row of staples.

Generally stated, the object of the invention is to provide a novel and improved 20 carton blank guiding device of the foregoing general character.

It is also an object to provide an improved construction and arrangement whereby the use of certain features of construction here- 25 tofore considered necessary or desirable is avoided.

It is also an object to provide certain details and features of construction tending to increase the general efficiency and desirability of a carton blank guiding device of 30 this particular character.

To these and other useful ends, the invention consists in matters hereinafter set forth and claimed.

35 In the accompanying drawings:—

Figure 1 is a front elevation of a stapling machine embodying the principles of this invention.

Fig. 2 is a plan of the work-guiding and 40 supporting device shown in Fig. 1.

Fig. 3 is a side elevation of the construction shown in Fig. 1, showing the folded carton blank in end elevation, and in position to be moved forward under the stapler.

45 Fig. 4 is a perspective of the said work-guiding and supporting device.

As thus illustrated, the invention comprises a body or table 1 of any suitable character, upon which a stapler 2 of any suitable 50 known or approved character is mounted. This stapler is arranged in position to drive

the staples downward upon the clenching device 3 mounted on the end of the flexible bar 4, which latter is of any suitable or desired length, depending upon the size of the carton blanks to be stapled. Said bar 4 is flexibly supported by a flexible coil or convolution 5 which is rigid with the upright supporting portion 6, the latter having a boss 7 provided with a bolt opening 8 by which 55 the entire device is either rigidly or pivotally supported on the bracket arm 9 fastened to the stapler head. It will be seen that the coil or convolution 5 starts at the outer side of the supporting portion 6 and 60 extends outward and rearward and downward, in flat form, until it reaches the plane of the bar 4, and then curves forward until it unites with the outer end of the bar 4, 65 whereby the portion 6 is a distance above the top surface of said bar. Also, it will be seen that the upper horizontal portion 10 of said coil or convolution serves as a support for the upper flap 11 of the carton blank, the inclined portion of the coil or convolution 5 70 extending upward to this horizontal portion 10, whereby the flap 11 will slide upwardly into position thereon. Also, it will be seen that the lower flap 12, when the carton blank is pushed forward, rests upon the 75 top of the bar 4, whereby this lower flap passes under the portion 6, the outer end of the latter being rounded at 13 to deflect the flap downward as it is pushed into place. Also, it will be seen that the coil or convolution 80 85 90 95 100 5 has a gage 14 which engages the longitudinal edge of the flap 12, thereby to properly position the flaps in the guiding device for movement forward upon the top surface of the bar 4 to receive the row of staples. The portion 6 also serves as a gage to engage the longitudinal edge of the flap 11, and in this way lateral displacement of the carton blank is prevented. Each time the stapler drives a staple, the downward pressure thereof upon the two thicknesses of the blank (11 and 12) resting on top of the clenching device 3, forces the end of the bar 4 downward against the rest or support 15 on the body of the machine. This downward movement of the bar may be insured merely by the springy or resilient or flexible char-

acter of the coil or convolution 5, or if the latter be made stiff and rigid, then the pivot 16 extending through the bracket 9 and the opening 8 to the boss 7 will allow the bar to 5 tilt downward.

In operation, the carton blank is introduced into the guiding device, with the lower or flat body portion 17 of the blank resting upon the top surface of the table 1, 10 and with the flaps 11 and 12 resting respectively upon the ledge 10 and the bar 4, as previously described. The top flap 11 sags down and rests upon the lower flap 12, after leaving the ledge 10, and the two flaps thus 15 resting one upon the other slide forward on top of the bar 4 and upon the clenching device 3 to receive the staples. The staples are driven successively, thereby to form a row 20 extending longitudinally of the lapping portions of the carton. The body portion 17 of the carton blank is deflected downward below the bar 4 by the rounded outer end portion of the gage 14, so that the latter serves not only as a gage for the purpose previously described, but also as a means for 25 deflecting the carton under the bar, when the end of the folded carton is pushed forward into place.

Thus it will be seen that the bar 4 is supported at its extreme end, and is thus balanced against any tendency to tilt sidewise under the downward pressure of the stapler, the support being of such character that the bar does not have a tendency to sag or tilt 30 downward at either side thereof. Also, with this construction, the production or manufacture of the structure is facilitated, so that the cost thereof is less than in other cases. Also, the construction tends to facilitate the adjustment and manipulation of the folded carton blank, and serves to accurately 35 guide the latter forward under the stapler.

It will be understood, of course, that the gage 14 may be omitted, as the portion 6, by 40 engaging the longitudinal edge of the flap 11, will properly position the folded blank in the guiding device. The coil or convolution 5 forms an approach to the horizontal portion 10, which latter forms a ledge over the bar 4 to support the upper flap of the blank, and this approach formed by the coil or convolution guides the upper flap onto 45 said ledge while the lower flap passes below the ledge. In this way, the ends of both flaps can rest one on top of the other on the coil or convolution, and can then be pushed forward, the upper flap rising automatically onto the ledge 10, and the lower flap entering automatically below this ledge and sliding 50 forward on the bar to thereafter receive thereon the upper flap as soon as the latter begins to sag downward after leaving said ledge.

It will be seen that the portions 5 and 10

practically form a spiral, one end of the 65 spiral terminating at the rear end of the bar 4, and the upper end of the spiral terminating in the element 6 by which the spiral and the bar are supported. This spiral formation provides the necessary support for the 70 bar 4, in a manner that permits the proper feeding of the blank into position to be stapled and allows the free end of the bar to spring up and down during the stapling operation. 75

What I claim as my invention is:—

1. In a machine for stapling a folded carton blank, a bar to support the lower flap of the blank, a guiding device to support said bar, said device extending over the bar and then rearwardly to the rear end thereof, in such manner as to provide a support for the upper flap of the blank, said bar being disposed in position to support one flap on top of the other, after the two flaps pass beyond 85 said guiding device, thereby to receive the staples.

2. A structure as specified in claim 1, said guiding device having a gage to engage the longitudinal edge of the upper flap. 90

3. A structure as specified in claim 1, said device being in the form of a coil or convolution extending gradually around into alignment with the bar. 95

4. A structure as specified in claim 1, said device having a gage to engage a longitudinal edge of the lower flap of the blank. 100

5. A structure as specified in claim 1, said guiding device being in the form of a coil or convolution which extends outward and 105 rearward from a point over said bar and then inward and forward to the rear end of the bar, so that the bar and device are rigidly connected together, and said device being flexible to permit the other end of said bar to move downward under the pressure of the stapler.

6. In a device for guiding the upper and lower flaps of a folded carton blank into position for stapling, the combination of a bar to support the lower flap, a ledge above the bar to support the upper flap in position to move forward onto the lower flap, so that both flaps will then move forward in superimposed condition on the bar, as the blank 110 is advanced toward the stapling position, and means forming an approach to said ledge to guide the upper flap thereto while the lower flap passes below the ledge. 115

7. A structure as specified in claim 6, said means comprising an incline leading up to said ledge from the plane of said bar. 120

8. A structure as specified in claim 6, said means forming a support for said bar.

9. In a stapling machine, the combination 125 of a bar to support two thicknesses of material thereon, means for operating upon the material to secure the two thicknesses to

gether, thereby to form a lap seam, and a spiral support for the bar.

10. A structure as specified in claim 9, the lower end of the said spiral terminating at the end of the bar, and the upper end of the spiral being rigidly supported, so that the upper end portion of the spiral extends over the bar, and whereby the said spiral support forms a guide for the two thicknesses of 10 material, the upper portion of the spiral ex-

tending between the two thicknesses, thereby to guide the two thicknesses forward upon the bar.

11. A structure as specified in claim 9, said spiral support having means for engaging 15 the edge of the lower thickness of the material.

Signed by me at St. Joseph, Michigan,
this 10th day of January, 1918.

EDWARD CRAIG.
